UNITED STATES PATENT OFFICE.

CHARLES W. FELLGREN, OF CHICAGO, ILLINOIS.

BUILDING CONSTRUCTION.

1,218,385.

Specification of Letters Patent.

Patented Mar. 6, 1917.

Application filed February 20, 1914. Serial No. 819,923.

To all whom it may concern:

Be it known that I, CHARLES W. FELLGREN, a citizen of the United States, and a resident of the city of Chicago, county of Cook, and State of Illinois, have invented certain new and useful Improvements in Building Constructions, of which the following is a specification.

My invention relates to improvements in building constructions and more especially to floor constructions therefor, the object of the invention being to provide a simple and reliable concrete floor construction which is indestructible by fire, and which may be readily repaired in case of fire.

The invention consists in the combinations and arrangements of parts hereinafter described and claimed.

The invention will be best understood by reference to the accompanying drawing forming a part of this specification, and in which,

Figure 1 is a perspective view partially in section of a floor construction embodying my invention, and

Fig. 2, a transverse section of the same.

The preferred form of construction, as illustrated in the drawing comprises a concrete body 3 having securing members 4 and 5 embedded therein and extending therethrough. Each of the members 4 and 5 is provided with ends 6 which project from each side of the body 3 and are offset with respect to the body portions of said members so as to be more securely anchored in body 3. Each of the securing members 4 and 5 is provided at one edge adjacent the bottom thereof with a laterally opening downwardly extending notch 7 and in the other edge adjacent the top thereof with a laterally opening downwardly extending notch 8. Transverse rods or bars 9 and 10 are inserted in notches 7 and 8 respectively and other bars 11 are placed on bars 9 at right angles thereto. Bars 9 and 11 are secured in position by bending the edges of notches 7 in securing members 5 over bars 11 and by bending the edges 13 of notches 8 over bars 10, as shown. After the parts have been thus securely bound together, the concrete body 3 is formed thereover by providing any suitable form of a mold. The securing members 4 and 5 are arranged in rows with the

members in each row in transverse alinement with the members in the other rows so as to permit of the positioning of the bars 9 and 10, as set forth above. Also, the securing members 4 and 5 in each row are alternately arranged in opposite positions so that their projecting ends are distanced apart laterally to permit of the placing of wooden strips 14 therebetween. These strips 14 are secured in place by means of nails or screws 15 passed through perforations provided in the ends 6 and the flooring boards 16 are secured to the upper strips 14, and a ceiling 17 of the next room below is secured to the lower strips 14, thus completing the floor construction.

By this arrangement a strong durable construction is afforded and one in which in case of fire all that could be destroyed would be the floor or ceiling and the wooden strips 14. However, the projecting end 6 will remain and constitute a simple means for rebuilding the floor or ceiling, as will be readily understood.

While I have illustrated and described the preferred form of construction for carrying my invention into effect, this is capable of variation and modification without departing from the spirit of the invention. I, therefore, do not wish to be limited to the exact details of construction set forth, but desire to avail myself of such variations and modifications as come within the scope of the appended claim.

Having described my invention what I claim as new and desire to secure by Letters Patent is:

A floor construction comprising a concrete body; metallic securing members extending through said body and projecting from both sides thereof, the projecting ends of said members being offset from the body portions thereof and said members being provided with downwardly extending notches in their sides within said body, said members being arranged in said body, in rows, the members in each row registering with the members in the other rows and the adjacent members in each row being oppositely positioned so that said projecting ends are adapted to engage opposite sides of securing strips; transverse bars resting in said notches; bars arranged at right angles to

2
said transverse bars and resting thereon, the edges of said notches being bent over said last mentioned bars; wooden strips secured to the projecting ends of said securing members; flooring boards secured to the upper strips; and a ceiling secured to the lower strips, substantially as described.

In testimony whereof I have signed my name to this specification in the presence of two subscribing witnesses.

CHARLES W. FELLGREN.

Witnesses:

JOSHUA R. H. POTTS,

HELEN F. LILLIS.
